CLAIM

The ornamental design for a ceiling fan blade, as shown and described.

DESCRIPTION

FIG. 1 is a bottom front side and tip end perspective view of the ceiling fan blade.

FIG. 2 is a bottom rear side and root end perspective view of the blade of FIG. 1.

FIG. 3 is a top front side and root end perspective view of the blade of FIG. 1.

FIG. 4 is a top rear side and tip end perspective view of the blade of FIG. 1.

FIG. 5 is a bottom view of the blade of FIG. 1.

FIG. 6 is a top view of the blade of FIG. 1.

FIG. 7 is a front side view of the blade of FIG. 1.

FIG. 8 is a rear side view of the blade of FIG. 1.

FIG. 9 is a tip end view of the blade of FIG. 1; and,

FIG. 10 is a root end view of the blade of FIG. 1.

The broken lines seen in FIGS. 1-6 depict portions of the ceiling fan blade that form no part of the claimed design.
